UNITED STATES PATENT OFFICE.

JEAN FRANÇOIS GIROUX, OF MONTREAL, QUEBEC, CANADA.

FURNACE.

No. 857,617.

Specification of Letters Patent.

Patented June 25, 1907.

Application filed July 7, 1903. Serial No. 164,615.

To all whom it may concern:

Be it known that I, JEAN FRANÇOIS GIROUX, a citizen of France, residing in Montreal, Province of Quebec, Dominion of Canada, have invented certain new and useful Improvements in Furnaces; and I do hereby declare that the following is a full, clear, and exact description of the same.

This invention relates particularly to gas heated hot water furnaces for heating buildings, although the features thereof may be applied to advantage to the construction of other types of furnaces.

The invention has for its object to provide a furnace which will be economical in its action, simple in construction and from which the maximum efficiency will be obtained.

My invention may be said briefly to consist of a sectional water heating furnace each section whereof is provided with an independent heater having an independent control, all the heaters of the series being fed from a common feeder, and all the water sections of the series being fed from a common feeder and discharging into a concentrator which in turn discharges into a super-heater communicating with a distributor section from which the feed pipes of the heating system lead. The return flow is taken to the water feeder which communicates with the independent water section, and a portion of this flow section within the furnace is adapted to act as a pre-heater, while the feeder just mentioned is provided with an injector to accelerate the flow therethrough.

Other features of the invention will be hereinafter specifically described and pointed out in the claims. For full comprehension, however, of my invention reference must be had to the accompanying drawings forming a part of this specification in which similar reference characters indicate the same parts and wherein

Figure 1 is a transverse vertical sectional view of a furnace constructed according to my invention; Fig. 2 is a horizontal sectional view taken on line A. A. Fig. 1, looking down; Fig. 3 is a horizontal sectional view taken on line B. B. Fig. 1, looking down; Fig. 4 is a transverse vertical sectional view, taken on line D. D. Fig. 3; Fig. 5 is a horizontal sectional view, taken on line E. E. Fig. 1 looking down; Fig. 6 is a horizontal sectional view taken on line F. F. Fig. 1 looking down; Fig. 7 is a detail side view of my improved

arrangement of valve, for the regulation of the gas supplies; and Fig. 8 is a side elevation of the same means the view being taken right angles to Fig. 8.

The casing of my improved furnace is preferably of circular cross-section as at a, and has a square front b, the circular portion consisting of plates E of an arc to conjointly form the main portion, while the squared front portion has the front plate thereof, b', hinged to act as doors and the rear plates are also hinged for the same purpose. This body portion of the casing supports a dome C, which constitutes the super-heater, to be presently further described, and this main body portion is supported in turn upon a hollow base B supported in turn upon a stand A of sufficient height to allow for the connection of the return of the heating system.

The water heating sections, of which there are a series are disposed a short distance one above the other with a space between them just sufficient to accommodate a series of heaters, each water section being independently heated. These water sections correspond in structure, and each consists of a casting comprising an annular inclosing part K, and an inner curved section K', the outer and inner sections communicating at 85 their ends with one another as at K², which ends are closed by a plate K³ which has flow and return pipes K⁴ and K⁵ projecting therethrough at one end, the other ends of said pipes extending into a vertical cylindrical feeder I, and a vertical cylindrical concentrator J respectively, each of said pipes being controlled by a plug valve N. This construction of water heating section insures a duplex current therethrough, one portion of which circulates through the outer annular passage K, and the other portion circulates through the inner passage K'. The heaters correspond structurally with one another and each consists of a pair of heating members each of which is preferably of ear-form, and has its upper wall provided with a series of slots L' of progressively increasing area or length from the end adjacent to its supply pipe L² to the opposite end thereof, to insure uniformity of flow therefrom. The water heating sections are preferably flat on top and each passage thereof of semi-circular cross section on its underside.

A pipe H, having the return from the heat-

ing system communicating with the lower end thereof extends upwardly through the stand A to the lower end of the cylindrical feeder I, the upper portion of this pipe being 5 provided with a valve O.

In order to pre-heat the return before it enters the water-heating section, and at the same time, accelerate the flow through this feeder and consequently from the feeder 10 through the water sections and the system, I increase the diameter of the lower portion of pipe H and take a pipe e from the upper end thereof and upwardly, around the lowermost heater then horizontally into the lower end of 15 the feeder I wherein it is turned upwardly and provided with a nozzle e⁴. I also take a second pipe e' from the concentrator J and extend it in loop form and in two sections as at e² through the interior of the lower portion 20 of pipe H the other ends of these pipe sections being bent as at e³ and located to discharge into the lower end of the feeder I. This pipe e serves to conduct a small stream 25 of water at a high temperature and ejects it into the lower end of the feeder, the ejected water raising the temperature of the water in the feeder while the force of the ejection accelerates the flow. The pipe e' meanwhile 30 conducts a stream of water at a high temperature and the heat radiating therefrom raises the temperature of the water returning through H. If desired the pipe e' may be dispensed with if the circuit of the system is such as will insure the flow required.

35 The super-heater C is of volutoid form, as shown in Fig. 7, and consists of an open flat bottom and curved top or hollow section having a spiral partition C' therein, while the top thereof is cut away centrally and has the 40 lower end of a cylindrical section F connected thereto at its lower end, and at its upper end to a distributor head G from which the flow pipes G' of the heating system are taken.

45 The products of combustion are conducted from the interior of the furnace to any available chimney connection and the heat thereof is utilized by radiation as follows: A pipe F' is taken from the upper end of the interior 50 of the furnace upwardly through the center of the super-heater and through the cylindrical section F and the distributor head G to the chimney, and the lower end thereof has a truncated cone M secured rigidly there- 55 in with its truncated apex facing upwardly and its base closed and provided with a damper M'. The water is conducted from the concentrator J to the super-heater through a pipe R controlled by a valve R'.

60 The supply of gas to the burners is controlled by the following means: The gas is conducted to a distributor box T' controlled by a valve T² having a micrometric dial T³ concentric to the stem thereof, and an index 65 hand T¹ is mounted upon the valve stem and

indicates upon the dial the different angular positions to which the valve is turned, thus enabling the amount of gas flowing to the burners to be ascertained at a glance. A pair of pipes S connect this distributor box 70 to a pair of distributing sections U from which a series of pipes V lead to the burners, each burner member being connected to one of the pipes of this series while said pipes are controlled by valves V' and the pipes S are 75 controlled by valves S', the latter valves being provided with micrometric dials, and their stems with index fingers similarly to the valve T². This arrangement enables the burner members to be controlled either individually, by the valve V', by groups, by the valves S', or collectively by the valve T².

In order to enable hot water to be provided for domestic use, I locate a water-heating section W' similar to the sections, K, above 85 the series of water-heating sections, and provide same with flow and return pipes W' and W² respectively, which are connected to the hot water service pipes of the residence. I locate an independent burner X beneath 90 this heater W and connect same to the distributor box T by a pipe X' controlled by a valve X². During the seasons when the furnace is in operation there will be no need to use the burner X as the heat from the burners beneath the other water-heating sections will be sufficient; but at other seasons when the furnace will not be in operation, my invention provides for the independent supply 95 of hot water for domestic use.

I make the water-heating sections of aluminium on account of its high efficiency as a heat conductor, and its not being liable to oxidation, and its natural rigidity which permit of very thin metal being used.

I prefer to arrange the heaters in close proximity to the water-heating sections in order to get as close as possible to the zone of heat generation, thereby obtaining the highest possible results from the heaters.

What I claim is as follows:—

1. In a hot water heater for supplying hot water to a heat distributing system such heater having flow and return connections for effecting communication with the heating system, the combination with the heater and a supply pipe connected to the return connection of such heater of means in intimate relation with and for heating the water flowing through such supply pipe the latter means being independent of but controlled by the heating means.

2. In a hot water heater for supplying hot water to a heat distributing system such heater having flow and return connections for effecting communication with the heating system, the combination with the heater and a supply pipe connected to the return connection of the heater, of means for pre-heating the water flowing through such sup- 130

ply pipe, and means for super-heating the water flowing through the flow pipe of the Leater.

3. In a heater, the combination with an inclosing casing of a series of heating sections within said casing and having intake and outlet ports, a feeder within the casing and connected to and communicating with the intakes of all of said heating sections, a concentrator within the casing and connected to and communicating with the outlets of all of said heating sections, means for connecting the return of a heating system to said feeder, means for connecting the flow of such heating system to said concentrator, and means for heating said heating sections.
4. In a heater, the combination with an inclosing casing of a series of heating sections having intake and outlet ports, a feeder within said casing and connected to and communicating with the intakes of all of said heating sections, a concentrator within said casing and connected to and communicating with the outlets of all of said heating sections, means for connecting the return of a heating system to said feeder, means for connecting the flow of such heating system to said concentrator, an independent heat generator for each of said heating sections, and means for controlling the said heat generators individually, and said inclosing casing having a chimney connection.

5. In a water-heating furnace, the combination with an inclosing casing, of a series of water-heating sections having intake and outlet ports, a feeder connected to and communicating with the intakes of all of said water-heating sections, a concentrator connected to and communicating with the outlets of all of said water-heating sections, means for connecting the return of a heating system to said feeder consisting of a pipe through which said return flow passes, means for heating said pipe means for connecting the flow of such heating system to said concentrator, and means for heating said water-heating sections, said water-heating sections, feeder, and concentrator being all located within such inclosing casing, and said inclosing casing having a chimney connection.

6. In a water-heating furnace, the combination with an inclosing casing, of a series of water-heating sections having intake and outlet ports, a feeder connected to and communicating with the intakes of all of said water-heating sections, a concentrator connected to and communicating with the outlets of all of said water-heating sections, a pipe extending from said feeder downwardly toward the lower end of the furnace and a coil of pipe connected at one end to said last mentioned pipe, and extending horizontally and into the lower end of such feeder, means for connecting the flow of such heating sys-

tem to said concentrator, and means for heating said water sections, said water-heating sections, feeder, and concentrator being all located within such inclosing casing, and said inclosing casing having a chimney connection.

7. In a water-heating furnace, the combination with an inclosing casing, of a series of water-heating sections having intake and outlet ports, a feeder within the casing and connected to and communicating with the intakes of all of said water-heating sections, a concentrator within the casing and connected to and communicating with the outlets of all of said water-heating sections, means for connecting the return of a heating system to said feeder, means for connecting the flow of such heating system to said concentrator, an independent heat generator consisting of a gas burner located beneath and in close proximity to each of said water-heating sections, and means for controlling the supply of gas to each of said burners, and said inclosing casing having a chimney connection.

8. In a heater, a heating section consisting of an annular inclosing part, and an inner curved part independent of said inclosing part, said inclosing and inner parts communicating at their ends with one another, means for separating the joint intake ends from the joint outlet ends, and means for connecting the flow and return pipes to said joint intake ends and joint outlet ends respectively.

9. In a water-heating furnace, the combination with water-heating means, of means in communication with the water heating means of the furnace for super-heating the water flowing from such water-heating means, said super-heating means consisting of a section of volutoid form and horizontally arranged, and having only a single passage a water-conductor leading from the water-heating means to one end of the volutoid section, and effecting the said communication and a water-conductor leading from the opposite end of said volutoid section, for the purpose set forth.

10. In a water-heating furnace, comprising an inclosing casing, water-heating means within said inclosing casing, the combination with said water-heating means of means for super-heating the water flowing from said water heating means, said super-heating means consisting of a section of volutoid form extending completely across the upper end of said inclosing casing and having a central vertical passage therethrough, a water-conductor leading from said water-heating means to the outer end of said volutoid section, the inner end of said volutoid section having a vertical cylindrical section connected at its lower end thereto, a water distributing head connected to and communicating with the upper end of said vertical cylindrical

section, and having a central vertical passage therethrough, of a pipe for conducting the products of combustion from the interior of said inclosing casing, said pipe leading from the upper end of said interior of the casing upwardly through the passage in said volutoid section through said vertical section, and through said distributing head, and having a truncated cone at its lower end and communicating therewith, said cone having a valve for controlling the passage therethrough substantially as described and for the purpose set forth.

11. In a water-heating furnace, the combination with water-heating means consisting of a series of water-heating sections, and a series of gas burners, each burner of said series being in close proximity to and beneath the water-heating sections, of a separate water-heating section for heating water for domestic use, and a separate burner for said last mentioned section, and means for controlling the supply of gas to said burners individually, substantially as described and for the purpose set forth.

12. In a water-heating furnace, comprising a series of super-imposed water-heating sections, and a series of gas burners located beneath and alternating with and in close proximity to the water-heating sections of said series, the combination with said burners of a distributor box, a gas conducting pipe leading to said distributor box, a valve controlling said gas supplying pipe, a micrometric dial upon said valve concentric to the stem thereof, an index hand carried upon said stem in registering relation to said dial, a pair of distributing sections adjacent to said distributing box, a pair of gas conductors one of which connects said distributing box to one of said distributing sections and the other connects the distributing box to the other of said distributing sections, each of the before mentioned gas burners comprising a pair of gas burning members, a series of valve controlled gas pipes leading from one of said distributing sections, and one of said pipes being connected to each of said burner members, a series of pipes connecting the other distributing section to the other burner members, and each of the gas conductors connecting the distributing box to the distributing sections being provided with a valve, and each valve having a micrometric dial thereon concentric to its valve stem, and each valve stem having an index hand thereon in indicating relation to said dial, substantially as described and for the purpose set forth.

13. In a heater comprising a casing, heating sections within said casing, means effecting a communication between said sections, a flow pipe connected at one end to one end of said heating sections, and a supply pipe connected at one end to the opposite end of said heating sections, the combination with said heating sections and flow and supply pipes, of valvular means located in said flow and supply pipes for cutting off same from the heating sections.

14. In a heater, a heating section consisting of an annular inclosing part, and an inner curved part independent of said inclosing part, said inclosing and inner parts communicating at their ends with one another, means for separating the joint intake ends from the joint outlet ends, and means for connecting the flow and return pipes to said joint intake ends and joint outlet ends respectively, each of such sections having one side formed with convex heating surface.

15. In a water heating furnace, the combination with an inclosing casing of a series of water-heating sections having intake and outlet ports, a feeder connected to and communicating with the intakes of all of said water-heating sections, a concentrator connected to and communicating with the outlets of all of said water-heating sections, a pipe extending from said feeder downwardly toward the lower end of the furnace and offset, a coil of pipe connected at one end to the bend at the off-set, and extending horizontally and into the lower end of such feeder, a second pipe connected at one end to said concentrator and having its other end extended downwardly to the lower end of said pipe, and upwardly through the interior thereof, through the bend at the off-set, and extending horizontally and into the lower end of such feeder, means for connecting the flow of such heating system to said concentrator, and means for heating said water sections, said water-heating sections, feeder, and concentrator being all located within such inclosing casing, and said inclosing casing having a chimney connection.

In testimony whereof, I have affixed my signature, in presence of two witnesses.

JEAN FRANÇOIS GIROUX.
